UNITED STATES PATENT OFFICE.

OBERT W. BURKETT, OF DALLAS, TEXAS.

DESIGN FOR HOSIERY.

Application filed October 25, 1927. Serial No. 23,873. Term of patent 3½ years.

To all whom it may concern:

Be it known that I, OBERT W. BURKETT, a citizen of the United States, and a resident of Dallas, Texas, have invented a certain new, original, and ornamental Design for Hosiery, of which the following is a specification, reference being had to the accompanying drawing, forming part thereof.

In the drawing:

The figure is a side view of a stocking showing my new design.

I claim:

The ornamental design for hosiery as shown.

O. W. BURKETT.
